UNITED STATES PATENT OFFICE

WOLDEMAR HEINITZ, OF CHEMNITZ, GERMANY, ASSIGNOR TO SCHUBERT & SALZER MASCHINENFABRIK, AKTIENGESELLSCHAFT, OF CHEMNITZ, GERMANY

FLAT-KNITTING MACHINE

Application filed July 17, 1930, Serial No. 468,655, and in Germany December 15, 1928.

My invention relates to flat knitting machines and more particularly to the operating mechanism for the thread guides.

It is an object of my invention to so design 5 the aforesaid mechanism that a brake is set immediately upon the breaking of the connection of the thread guides with the operating mechanism.

To this end I provide the usual reciprocating rod for operating the thread guides, a frame which is adapted to be operatively connected with the reciprocating rod, means for connecting the frame with the thread guides, a brake adapted to arrest the frame, 15 and means for alternately connecting the frame with the reciprocating rod and for applying the brake.

In a preferred embodiment of my invention, I provide a fixed rod which is parallel 20 to the reciprocating rod, and may be arranged at the same level with, above or below the reciprocating rod, as desired, and is adapted to be engaged by the brake, and I further provide means for applying the 25 brake to the fixed brake rod immediately upon disconnecting the frame from the reciprocating rod.

It is another object of my invention to adapt the operation of the mechanism to 30 variations in the speed of the knitting machine.

To this end I provide a governor in combination with the usual fashioning mechanism which governor influences the position 35 of the checks for controlling the operation of the brake-guide operating mechanism in conformity with the variations of speed. Normally, that is, without the governor I provide, the checks are moved in accordance 40 with the fashioning of the work being knitted, but the variable relative velocity at which the checks are struck by a latch or other part on the frame for controlling the 45 mechanism, is not considered. The consequence is, that at high speeds the operation of the thread-guide operating mechanism is not timed exactly with respect to the fashioning mechanism. For instance, the operation 50 will be widely different for speeds of, say

20 rows per minute, and of 80 rows per minute.

In order to eliminate this drawback I so design the checks under the control of the fashioning mechanism that they are not 55 only displaced laterally, as in the normal operation of the fashioning mechanism, but in addition are raised and lowered by the governor in conformity with the speed variations of the machine. This results in a very 60 delicate adjustment of the checks but an even higher degree of exactitude is obtained by providing the checks with inclined operating surfaces so that not only the vertical and horizontal position of the checks with 65 respect to the latch or other part on the frame is varied, but the position of the point where the latch is engaged by the checks undergoes a further variation on account of the inclined faces of the checks. 70

In the drawings affixed to this specification and forming part thereof a machine embodying my invention is illustrated diagrammatically by way of example.

In the drawings

Fig. 1 is an elevation showing one end of the machine, partly broken away and viewed from the rear, i. e. from the side opposite the operator's position,

Fig. 2 is an end elevation of the machine viewed from the right in Fig. 1, and partly in section on the line II—II in Fig. 1,

Fig. 3 is a section on the line III—III in Fig. 1,

Fig. 4 is a plan view of the machine,

Fig. 5 is a section on the line V—V in Fig. 2,

Figs. 6-13 illustrate details of the brake operating mechanism as follows:

Figs. 6 and 7 are sections of the brake frame on the line VI—VI in Fig. 1, showing the parts of the mechanism in two distinct positions,

Fig. 8 is an elevation of the brake frame viewed as in Fig. 1, but drawn to a larger scale,

Figs. 9 and 10 are sections on the corresponding line in Figs. 6 and 7, respectively, and

Figs. 11, 12 and 13 show a check for co- 100

operation with the brake mechanism in end elevation viewed as indicated by the arrow XI in Figs. 8, in side elevation, and in plan view, respectively.

Referring now to the drawings and first to Figs. 1 and 4, 1 is the frame of the machine which will not be described in full detail as it is designed as usually, 2 is the main driving shaft of the machine, 3 is a spur gear on the main driving shaft, and 5 is a pinion 10 on a lay shaft 6 by which a governor 7 is operated through the medium of bevel gearing 8, 9.

The machine is equipped with the usual 15 thread-guide bars 10 and thread guides 11, Fig. 2, the bars being fitted to slide in slotted brackets 12 on the frame 1, which brackets are supported on a longitudinal bar 4. 13 is the usual reciprocating rod for actuating the thread guides, and 14 is a fixed rod for braking the thread guides. Reciproca- 20 tion is imparted to the rod 13 by any suitable means, not shown, while the fixed rod 14 is held in position by two brackets, 15, 25 16, Figs. 1 and 4. The brackets are held at their front ends by a support 101 on a flat bar 102 of the frame 1, and at their rear ends by a rod 103 on which they may be clamped with slotted eyes. Mounted to slide 30 on the rods 13 and 14 is a brake frame 17 which is slotted for the reception of the two rods, as best seen in Figs. 5. 18 is a pin which is fitted to slide in a sleeve 19 of the frame 17 against the action of a spring 20. The spring 35 is abutted on a shoulder 21 at the lower end of the sleeve 19, and supports the pins 18 by a flange 22. The portion of the pin which is above the flange 22 is equipped with a rack 23. 24 is a pinion in mesh with the rack 23, 40 and 25 is a shaft which is mounted to rotate in the frame 17 and on which the pinion 24 is secured. 26 and 27 are cams on the shaft 25, and 28 and 29 are double-armed rocking levers which are fulcrumed in the frame 17 at 45 30 and 31, respectively. 32 and 33 are blade springs which are operatively connected with the brake levers 28 and 29, respectively. Each spring cooperates with a block in the frame 17. One of the blocks is adapted to be 50 applied to the reciprocating rod 13 by the lever 29 and its spring 33, these parts constituting a clutch for connecting the frame 17 with the reciprocating rod 13 and the other block, which is shown in section at 34 in Fig. 55 10, is adapted to be applied to the brake rod 14 by the lever 28 and its spring 32, these parts constituting a brake. When the shaft 25 is rotated by the rack 23 on the pin 18, the cams 26 and 27 alternately operate the clutching lever 29 with its spring 33, and the brake lever 28 with its spring 32.

35 is a latch in the pin on the frame 17 at 60 36, and 37 is a tooth projecting forwardly from the latch 35 and adapted to engage a 65 notch 38 in the pin 18.

The thread-guide bars 10 are connected with the frame 17 by means of a dog 39 which is hinged in a block 40 at one end of the frame 17 and is adapted to engage projections 41 on the thread-guide bars 10, Figs. 1 70 and 4. Figs. 6 and 8 show the dog 39 in its inactive position with respect to the projections 41.

Means for controlling the pin 18, and consequently the brake lever 28 and the clutching lever 29, comprise a pair of checks 42 and 43, Fig. 1, and a reciprocating head 44. The checks 42 and 43 are reciprocated by the 75 fashioning mechanism, not shown, and are fitted to slide in brackets 45 and 46 with push-rods 91 and 92. The brackets in turn, are fitted to slide on bars 47 and 48, Fig. 1, under the action of the fashioning mechanism. The checks cooperate with the latch 35 which is normally held with its projection 37 in the recess 31 of the pin 18 by gravity but is thrown out by one of the checks, as shown for the check 42 in Fig. 6, when such check is struck by the latch 35.

49 is a roller at the upper end of the pin 18 which is adapted to be engaged by the reciprocating head 44. The means for imparting reciprocation to the head include a cam plate 50 on the driving shaft 2, with a concentric portion 51 and a cam portion 52. 90 53 is a roller which is adapted to cooperate with the concentric and the cam portions. 54 is a bearing block on the frame 1 in which a rocking lever 55 is fulcrumed on a horizontal pin at 56, Fig. 4. The rear end of the rocking lever is pivotally connected with a vertical rod 57 to the upper end of which the head 44 is secured. The vertical rod is fitted to slide in a sleeve 104 which is supported on a bar 105. The bar 105, in turn, is held by brackets 106, 107 on the bar 103.

58 is a pin at the front end of the lever 55 on which the boss of the roller 53 is fitted to rotate and to be displaced axially. By displacing the roller 53 it is alternately moved into operative connection with the concentric portion 51 and the cam portion 52. 95 59 is a second rocking lever which is also fulcrumed on the block 54, but about a vertical pin 60. The front end of the lever 100 engages a groove in the boss of the roller 53, while its rear end is engaged by a rod 61. This rod 61 forms part of a control mechanism which is actuated from a ratchet wheel 62 on a shaft 63, Fig. 1. The means for rotating the ratchet wheel at intervals are not shown. 64 is a chain or belt equipped with projections 65 and supported on a pulley 66 on the shaft 63 and a pulley 67 on the frame of the machine, 68 and 69 being guiding pulleys for the chain or belt. 70 is a bell crank lever which is fulcrumed at 71. One of its arms is provided with a hook 71 for cooperation with the projections 65 on the chain or belt 64. 73 is a rod by which the other end 105 110 115 120 125 130

of the bell crank lever 70 is connected with the ratchet lever 74. The ratchet lever 74 is mounted to rock on the frame 1. 75 is a pawl on the ratchet lever 74 and 76 is a ratchet wheel for cooperation with the pawl. 77 is a bearing on the frame 1 in which the shaft 78 of the ratchet wheel is supported, and 79 is a cam drum which is fitted on the shaft 78 with the ratchet wheel 76. The cam drum 10 79 has a set of cams 80 and a set of rocking levers 81, one per cam. In the present instance six levers have been shown. The levers 81, one per cam. In the present instance six levers have been shown. The levers 81, one per cam. In the present instance six levers have been shown. The first 15 lever 81 is connected with the rod 61 and the next rocking lever is connected with another rod 84 and another brake mechanism, not shown.

As often as the bell crank lever 17 is engaged by one of the projections 55 on the chain or belt 64, the ratchet wheel 75 is rotated for one pitch. The rotation is translated into rocking movement of the levers 81 by means of the corresponding cams 80 20 of the drum 79, and the movement of the lever or levers is transmitted to the roller 53, so as to change its position with respect to the concentric and cam portions 51 and 52.

As mentioned, the checks 42 and 43 are fitted 25 to slide in the brackets 45 and 46. This sliding arrangement is provided with the object of controlling the checks by the governor 7 so as to vary their position with respect to the latch 35. To this end the spindle 85 30 of the governor is equipped with an anti-friction bearing 86 at its upper end, Fig. 2, which may be a ball or roller bearing, as desired. The anti-friction bearing 86 cooperates with a lever 87 which is fitted to rock 35 about a short pin 88 on the frame of the machine, with its free end bearing on the anti-friction means 86. 97 are anti-friction means, such as a ball or roller bearing, provided on the upper face of the lever 87, and 40 45 98 is a rocking lever on a shaft 96 which bears on the anti-friction means 97. 89 and 90, Fig. 4, are bearings in which the shaft 96 is fitted to rock, 94 and 95 are levers which are secured on the shaft in the vicinity of 45 50 the push rods 91, 92 and 93 is a rail which connects the free ends of the levers and engages below the lower ends of the push rods 91, 92 so that the push rods are displaced in the brackets 45 and 46 under the control 55 of the governor 7. By interposing the rail 93 intermediate the parts controlled by the governor 7 and the ends of the push rods 91 and 92 the action of one-sided forces is balanced so that the push rods move freely in 60 65 their brackets 45 and 46. This is necessary as the operation of the fashioning mechanism is very delicate and must not be interfered with by friction resulting from such forces.

65 As shown in Figs. 11 to 13, the checks 42

and 43 are provided with inclined faces for cooperation with the latch 35. In this manner the exactitude of the adjustment of the checks with respect to the latch is further increased as will appear from the description 70 of the operation.

Assume that the pin 18 has been depressed by the reciprocating head 44 acting on the roller 49, as shown in Fig. 6, and that the reciprocating rod 13 moves toward the left in Fig. 1. The depressed pin is locked in its position by the projection 37 of the latch 35 which engages the notch 38 of the spring by gravity. In this position of the pin 18 the cam 27 raises the rear end of the clutching lever 29 forcing down the spring 33 and the block allotted to the reciprocating rod 13 while the cam 26 is disengaged from the brake lever 28 so that no tension is put on the spring 32 for the brake rod 14, and the frame 17 is 80 free to move with the rod 13. When the dog 39 is engaged with one of the projections 41 on the thread-guide bars 10, the bar, or bars, which has thus been engaged, is entrained by the rod 13. When the stroke of the thread-guide bar, or bars, has nearly been completed, the latch 35 strikes the check 42 and its projection 37 is forced out of the notch 38 of the pin 18. The spring 20 now jerks the pin 18 upwards, as shown in Fig. 7, the head 44 having previously been retracted as will be described. The shaft 25 is now again rotated and the cam 26 raises the rear end of the brake lever 28, forcing down the spring 32 and setting the brake-block 34 on the brake-rod 14, while at the same time the spring 33 for the reciprocating rod 13 is released by the clutching lever 28, so that it is free to perform its normal movement while the frame 17 is arrested immediately upon engagement 95 of the checks 42 with the latch 35, and the thread-guide bar 10, or bars, which is connected with the frame 17 by means of the dog 39, is also arrested immediately.

When the rod 13 has arrived at the left-hand end of its stroke it starts for its return stroke to the right. In the meantime, through the medium of the belt 64, the drum 79 has been rotated and the roller 53 has been transferred to the cam portion 52 of the cam 50 100 from its concentric portion 51. This causes lowering of the head 44 through the medium of the mechanisms described, the pin 18 is depressed and locked by the latch 35, as described, while at the same time the spring 32 allotted to the brake rod 14 is released and the frame 17 is connected with the reciprocating rod 13 by the spring 33. The frame 17 is now entrained by the reciprocating rod 13 105 but in the opposite direction, until the latch 35 strikes the check 43 whereupon the pin 18 is jerked up by the spring 22, the head 44 having again been retracted. The connection of the frame with the reciprocating rod 13 is 110 115 120 125 130

broken while the brake is set on the brake rod 14.

The function of the governor 7 is to make up for irregularities in the speed of the machine. When the speed increases, the spindle 85 is raised, raising the lever 87 and rocking it about the pin 88. The movement of the lever is transmitted to the rail 93 by the means described and the checks 42 and 43 are raised so that another point of the inclined face of each check is struck by the latch 35. Therefore, when the speed is too high, the connection of the frame 17 with the reciprocating rod 13 will be interrupted and the frame 17 will be arrested at an earlier moment, while, conversely, when the speed becomes too low, the checks 42, 43 are set by the governor so as to retard the moment at which the frame is disconnected from the rod 13 and arrested by being connected with the brake rod 14. In this manner it is possible to effect the operation of the brake in conformity with the speed, and, as mentioned, to time it very exactly by properly determining the inclination and configuration of the faces at the checks 42 and 43.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:—

40 1. A flat knitting machine having thread guides and mechanism including a reciprocating rod for operating said thread guides and comprising a frame, means for connecting the frame with said thread guides, a 45 brake on said frame, a fixed brake rod on said machine, and means for alternately connecting said frame with said reciprocating rod and for applying said brake to said fixed rod.

50 2. A flat knitting machine having thread guides and mechanism including a reciprocating rod for operating said thread guides and comprising a frame, means for connecting the frame with said thread guides, a 55 brake on said frame, a fixed brake rod on said machine, means for alternately connecting said frame with said reciprocating rod, and for applying said brake to said fixed rod, and means on said machine for controlling 60 said connecting and brake-applying means.

65 3. A flat knitting machine having thread guides and mechanism including a reciprocating rod for operating said thread guides and comprising a frame, means for connecting the frame with said thread guides, a

brake on said frame, a fixed brake rod on said machine, means including a reciprocating pin on said frame, a latch for locking said pin, a pair of checks operatively connected with the fashioning mechanism of said machine for throwing out said latch, a reciprocating head operatively connected with a continuously moving belt on said machine and adapted to return said pin to the position in which it is locked by said latch, and means operatively connected with said pin for alternately connecting said frame with said reciprocating rod and for applying said brake to said fixed rod.

4. A flat knitting machine having thread guides and mechanism including a reciprocating rod for operating said thread guides and comprising a frame, means for connecting the frame with said thread guides, a brake on said frame, a fixed brake rod on said machine, means including a reciprocating pin on said frame, a latch for locking said pin, a pair of checks operatively connected with the fashioning mechanism of said machine for throwing out said latch, means under the action of the speed variations of said machine for varying the position of said checks with respect to said fashioning mechanism, a reciprocating head operatively connected with a continuously moving belt on said machine and adapted to return said pin to the position in which it is locked by said latch, and means operatively connected with said pin for alternately connecting said frame with said reciprocating rod and for applying said brake to said fixed rod.

5. A flat knitting machine having thread guides and mechanism including a reciprocating rod for operating said thread guides and comprising a frame, means for connecting the frame with said thread guides, a brake on said frame, a fixed brake rod on said machine, means including a reciprocating spring-controlled pin on said frame, a latch for locking said pin, a pair of checks operatively connected with the fashioning mechanism of said machine for throwing out said latch, a reciprocating head operatively connected with a continuously moving belt on said machine and adapted to return said pin to the position in which it is locked by said latch, and means operatively connected with said pin for alternately connecting said frame with said reciprocating rod and for applying said brake to said fixed rod.

6. A flat knitting machine having thread guides and mechanism including a reciprocating rod for operating said thread guides and comprising a frame, means for connecting the frame with said thread guides, a brake on said frame, a fixed brake rod on said machine, a reciprocating pin on said frame, means for moving said pin in opposite directions, a shaft adapted to be rotated upon
